UNITED STATES PATENT OFFICE.

RALPH B. HEAD, OF DENVER COLORADO.

TELEPHONE-METER.

1,042,790.

Specification of Letters Patent.

Patented Oct. 29, 1912.

Application filed February 23, 1911. Serial No. 610,306.

To all whom it may concern:

Be it known that I, RALPH B. HEAD, a citizen of the United States, residing at Denver, in the county of Denver and State of Colorado, have invented certain new and useful Improvements in Telephone-Meters, of which the following is a specification.

This invention relates particularly to meters for telephone service, but, as will be readily seen, it is adaptable to any and all uses wherein it is desired to place in the hands of the subscriber or user the control of the registration of the number of times he has used a certain intermittently operated utility subscribed to or rented by him. The invention will therefore be described with reference to its general use, as well as with reference to its specific use, in connection with telephone systems.

The principal object of the invention when applied to a telephone system, for example, is to automatically register at a given subscriber's telephone each call in response to which a proper connection has been made with any telephone and refuse to register each call in response to which a proper connection with any telephone has not been made.

The invention therefore consists in the construction of parts and in their combination for the purpose specified substantially as hereinafter set forth.

In the accompanying drawings which form a part of this specification Figure 1 represents the improved meter in side elevation, the casing being in vertical section; Fig. 2 is a like view of the same, showing the movable parts of the meter in one position occupied by them during the operation of the meter; Fig. 3 is an underside plan of the meter, the casing being in horizontal section; Fig. 4 is an end elevation of the instrument, the casing being in transverse vertical section; Fig. 5 is a vertical transverse section through the meter, as seen in Fig. 1, said section being taken in the plane indicated by the line 5-5; Fig. 6 is a vertical transverse section through the meter, as seen in Fig. 1, said section being taken in the plane indicated by the line 6-6; Fig. 7 is a plan of a part in detail; and Fig. 8 is an enlarged elevation of the rear end of the push-button.

The gist of this invention resides in the construction and equipment of a meter-con-

trolled system giving to the subscriber or user of a telephone or like instrument, the control of the registration of the number of times that he has used the telephone or like instrument. In accomplishing this there is located at the subscriber's station an instrument substantially such as illustrated in the accompanying drawings, which requires that the subscriber shall set an actuating means in a certain position without operating the meter. Then when the subscriber has obtained his telephonic connection, or has accomplished whatever other purpose he desired, over the particular system in which the meter is incorporated, the operator at the distant station will actuate any suitable means, preferably electro-magnetic means, for releasing the actuator set by the subscriber so that it may return to normal position and in returning to normal position actuate the counter of the meter. This invention also contemplates sounding a signal at both ends of the line when the meter has been actuated. It also contemplates the return of the actuator to normal position through the agency of the operator at the distant station when he has been unable to make the desired connection and without actuating the counter of the meter. This failure to get the connection will also be signified by the failure of the signals to sound. Obviously, these purposes may be accomplished by mechanisms of various designs and construction and coupled up in various electrical systems. In the accompanying drawing and in this specification attempt will be made to disclose in the broad, general way an apparatus which shall be capable of accomplishing the purpose of this invention, and yet shall simply be typical of such apparatus.

In the drawings 10 refers to any suitable form of case for housing the meter and its actuating parts. 11 refers to a frame mounted within the casing and so constructed as to form a suitable support for the various parts of the meter-actuating and controlling device. To one arm of this frame there are connected polarized electro-magnets 12 and 13, whose permanent magnet appears at 15. These magnets have protruding cores or poles at 16 and 17, respectively. The frame 11 has another arm as 18, extending horizontally below the magnets, and at the forward end of this arm there is an upright 110

post 19. On this post is pivoted the armature 20 of the polarized magnets. Upon the plate 20 are formed bosses 21 and 22 pitted in the usual manner to receive the points of 5 the pivot bearings carried by the post 19, as at 23 and 24. The lower pivot 24 is preferably formed upon a projection extending horizontally from the lower end of post 19 through an aperture 25 in the armature 20. 10 This projection forms a support for the circuit maker, whose terminals are indicated at 26 and 27, respectively. To hold the armature 20 in normal position and to return it to said position after actuation, any 15 suitable spring may be used such as the arc-shaped plate spring 28, secured at its middle to the upper end of post 19. It is also preferable to perforate the armature 20 for the reception of the pole-pieces 16 and 17, as indicated, in order that it may be more sensitive to the attraction of the magnets 12 and 13.

The term service-meter may apply properly to the whole device and therefore we 25 will term the part which shows the number of calls registered the counter. This counter may be of any desired and well known pattern and is indicated in the drawings at 29 as located at a window in one side of the casting 10, Figs. 3 and 4. The bifurcated crank 30 for operating the wheels of the counter is seen in Fig. 4, and it is actuated by the curved arm 31, pivoted to the underside of the counter case. The counter 29 may be 35 supported upon a projection of arm 18, as represented at 32'. Referring to Fig. 4, it is by the swinging of arm 31 on its pivot to draw the crank 30 to the left that the counter is operated.

40 The actuator of the meter, which is to operate the counter when the desired connection with the station called has been established and which has to return to normal without operating the counter when such 45 connection has not been made, is shown in the drawings as having a carriage 32 provided with upwardly extending headed projections 33 and 34, the heads of which are located in run-ways formed in the lower 50 surface of the arm 18. This run-way opens into a bore made longitudinally of the arm 18, in which is located a spring 35, preferably, about the core or rod 36. Extending upwardly from the headed projection 33 is 55 a perforated post 37 through which the rod 36 may pass and between this post and the opposite end of the bore in arm 18 the spring 35 is confined. This spring, as will appear, is for the purpose of returning the carriage 60 32 to normal position, Fig. 1. To the farther end of the carriage 32 there is hinged for lateral movement a spring-arm 38, which carries at its free end on a vertical axis a roller 39. The farther end of the arm 18 65 is downwardly inclined and terminates at

the same horizontal level as the lower end of the plate armature 20 in order that when the carriage 32 is pushed inward the wheel 39 will be forced downwardly along this incline until it has passed the plate 20, when 70 by virtue of the resiliency of the spring-arm 38 said roller will be forced upward at the farther side of the plate 20. The hub of wheel 39 will then press together the contacts 26 and 27 of the circuit maker. Projecting laterally from the spring-arm 38 in proximity to the wheel 39 is an arm 40', which, when desired, shall engage with the actuating arm 31 to operate the counter. The means shown in the drawings for driving 75 the carriage 32 inward consists of a push-button 41 at the inward end of which is a rod 42 mounted to ride through an opening in the lug 43, which extends downwardly from the arm 18 of the frame 11. A spring 80 40 encircles the rod 42 for returning the push-button to normal position and a screw 85 as 44 is located in the lower end of the stud 43 and has its upper end extending into a slot on the underside of the rod 42 to hold 90 the push-button in a certain fixed relation to the carriage 32. At the inner end of the push-button 41 on its upper side there is mounted a pawl 45 for engagement with the forward end of the carriage 32. This pawl 95 is mounted on a horizontal pin 46 between projections of the push-button and is engaged by a spring located about said pin, which spring allows a side-wise movement of the pawl upon the pin 46 and also returns 100 the pawl to the operative position seen in Fig. 1, when in the actuation of the mechanism it has been moved from such position. To provide for the free lateral movement of the pawl 45 the aperture therein, by which 105 it is mounted on pin 46, is vertically enlarged, at the side toward said spring, as indicated in Fig. 8.

110 It is intended that when the push-button is pressed inward the pawl 45 shall drive inward the carriage 32 and when the wheel 39 has passed over and caught upon the lower end of armature 20 the push-button may return to its normal position and will not again affect the position of the carriage no 115 matter how often it may be pressed, until the carriage shall have been returned to its normal position through the movement of the armature 20, actuated by its controlling magnets. To accomplish this a plate 47, 120 such as represented in detail in Fig. 7, is provided. This plate has in it an L-shaped slot 48 for the reception and guidance of the pawl 45. To effect this object the guiding-plate is pivoted at its inward end to a lug 125 49 on the stud 43 and at its outer end it is supported on a pin 50, mounted in a projection 51 from the frame 11. A spring, as 52, is mounted between the head of the pin 50 and the outer end of the plate 47 for hold- 130

ing said plate against a lug 53, which projects downwardly from the carriage 32, and serves to return the plate 47 to the position such as will permit the pawl 45 to spring back into the L-shaped slot when the carriage 32 has been returned to normal position.

In the operation of this service-meter upon pushing the button 41 inward, pawl 45 engages with the carriage 32 and drives it forward until the wheel 39 has passed beyond the lower end of the armature 20 and has sprung upward in position to be held by the armature 20 so long as said armature remains in normal position. As the push-button is pressed inward the pawl follows the long arm of the L-shaped slot until the wheel 39 has passed up behind the armature 20 and closed the circuit between contacts 26 and 27, when the pawl will be forced over into the short arm of the L-shaped slot by the spring upon pin 46. Then upon the release of push-button 41 its spring will return the button to normal position, Fig. 1. In this return movement the pawl 45 rides along the underside of plate 47 and will continue to ride along the underside of said plate in subsequent operation of the button until the carriage 32 has been released and returned to normal position. The carriage in returning to normal position will, by means of the lug 53, push the plate 47 laterally at its outer end until it brings the outer end of the L-shaped slot 35 over the pawl 45, then said pawl will spring up into said slot and be in position to again engage and drive the carriage 32 to

To provide for so directing the return of the laterally moving arm 38 with its projecting, actuating pin 40' in a manner such that if connection has been made with the distant telephone it shall actuate the counter and when such connection has not been made it shall return without actuating the counter, means are provided for tilting the armature 20 to one magnet or the other, according to the circumstances just specified. Such tilting of the armature will permit the roller 39 to move off at one side or the other 50 of the downward projection of the armature 20. If said roller moves off the plate 20, toward the side of the case where the counter 29 is mounted, then the pin 40' will in passing from position seen in Fig. 2 engage with the curved arm 31 which in turn will swing the crank 30 and actuate the counter. If the roller is thrown off the lower end of plate 20 to the opposite side, then the pin 40' will be carried past the 55 arm 31 without actuating it, as is clearly seen from the position of parts in Figs. 3 and 4. To insure this a downwardly projecting flange 54 is provided on the inward end of the arm 18. To provide for returning the spring-arm 38 into alignment with

the carriage 32 any suitable spring may be employed, such for instance as a wire 55 secured to the underside of the carriage 32 and passing at its inner end through a loop on the underside of the arm 38. This 70 spring will insure the proper location of the roller upon the lower end of the armature 20 when the carriage has been pushed inward in setting the meter for actuation by the operator at the distant or central station.

When the meter is used in a telephone system the circuit closed by the wheel 39 between the terminals 26 and 27 is the same circuit as that closed by the telephone hook 80 in taking down the receiver, substantially as indicated at 56. Therefore it will be seen that the subscriber in order to get his connection must set his meter in position to be actuated by the operator at central. 85

The control from the distant station, as has already been intimated, is by means of the polarized magnets. This control may be effected over any suitable circuit, such, for instance, as that typified in Fig. 3, 90 wherein at the distant station there may be located a polarity switch 56' for throwing the current either in one direction or the other from a source of current indicated at 57 through the magnets 12 and 13, depending upon whether the positive impulse is to cause the actuation of the counter or whether a negative impulse is to effect such actuation.

Any suitable connection may be made 100 with the counter for giving a signal at one or both ends of the line to indicate the operation of the counter. The means by which this signaling may be effected is typified in Fig. 4, wherein a signal-bell 58 is represented at the local station and another as 59 at the distant station, the source of current being indicated at 60 and the circuit closer indicated at 61 for operation by a finger 62 carried by the crank 30 of the 110 counter 29.

Thus it may be seen that with an apparatus, in a telephone system, such as above outlined a telephone subscriber, for example, will have an absolute check upon the central station with respect to the number of calls with which he should be charged. No attempt has been made to illustrate this service-meter as actually coupled into an existing telephone system, or in any other system, where service of a general utility is to be checked up, since such circuiting would depend upon the particular use to which the apparatus may be applied and is within the province of the skilled electrician.

The invention claimed is,

1. In an electrically controlled meter, the combination with the counter, of an automatic actuator therefor, a push-button independent of the actuator for advancing said 130

actuator to set it in operative position, a spring for returning the push-button alone to initial position, a pawl carried by the push-button for engagement with the actuator and means for putting the pawl out of operation until the actuator returns to initial position.

2. In an electrically controlled meter, the combination with the counter, of an automatic actuator therefor, a push-button for advancing said actuator to set it in operative position, a spring for returning the push-button to initial position, a spring pawl on the push-button in position to engage the actuator to advance it, and a slotted guiding plate for throwing said pawl out of operative position on the return of the push-button to initial position.

3. In an electrically controlled meter, the combination with the counter, of an automatic actuator therefor, a push-button for advancing said actuator to set it in operative position, a spring for returning the push-button to initial position, a spring pawl on the push-button in position to engage the actuator to advance it, a slotted guiding plate for putting said pawl out of operative position, and means moved by the actuator on its return to initial position for setting said plate into position for restoring the pawl to operative condition.

4. In an electrically controlled meter, the combination with polarized electro-magnets, a circuit-controller therefor at a distant station, a tilting armature for actuation by said magnets, a counter, a reciprocating carriage carrying a pin for actuating said counter, manual means for advancing said carriage, automatic means for returning said carriage, and a holding device on the carriage for engaging the tilting armature.

5. In an electrically controlled meter, the combination with polarized electro-magnets, a circuit controller therefor at a distant station, a tilting armature for actuation by said magnets, a counter, a reciprocating carriage, manual means for advancing said carriage, automatic means for returning said carriage, a spring arm hinged to said carriage, a pin carried by the free end of said arm for actuating said counter, a roller on the free end of said arm and adapted to engage with said armature for holding the carriage in advanced position.

6. In an electrically controlled meter, the combination with polarized electro-magnets, a circuit controller therefor at a distant station, a tilting armature for actuation by said magnets, a counter, a reciprocating carriage, manual means for advancing said carriage, automatic means for returning said carriage, a spring arm hinged to said carriage, means for normally holding said arm in alignment with the carriage, a pin carried by the free end of said arm for engaging the actuating arm of said counter, a roller on the free end of said spring arm for engaging with said armature to hold the carriage in advanced position, and means for guiding said pin into or out of engagement with the actuating arm of the counter when the carriage is returning to initial position.

In testimony whereof I affix my signature in presence of two witnesses.

RALPH B. HEAD.
